UNITED STATES PATENT OFFICE.

GUSTAV CIMIOTTI AND FERDINAND F. CIMIOTTI, OF NEW YORK, N. Y.

MACHINE FOR CLIPPING SEAL AND OTHER SKINS.

SPECIFICATION forming part of Letters Patent No. 240,007, dated April 12, 1881.

Application filed October 20, 1880. (Model.)

To all whom it may concern:

Be it known that we, GUSTAV CIMIOTTI and FERDINAND FLORIAN CIMIOTTI, both of the city, county, and State of New York, have invented certain new and useful Improvements 5 in Machines for Clipping Seal and other Skins, of which the following is a specification.

Every seal-skin has, besides the soft fine hair or wool which forms the main attraction of the 10 skin, long glossy hair or bristles—the so-called “water-hair”—the greater part of which is removed in dressing the skin. The shorter bristles, however, remain in the skin, and have to be removed by clipping or plucking. This 15 has heretofore been accomplished by hand, the operator blowing the fine hair back so as to expose the long and stiff bristles, which are then either cut off short or pulled out by pinchers. This method of clipping or plucking the 20 thick hair is slow, tedious, and expensive, and requires skilled hands.

The object of this invention is to furnish a machine by which the thick water-hair or 25 bristles of the fur can be removed in a rapid, uniform, and reliable manner; and the invention consists of a knife-edged bar, over which the seal-skin is tightly stretched and intermittently fed by means of winding and unwinding rollers. The narrow portion or strip 30 of the skin directly over the knife-edge is exposed to a vertical blast of air from a bellows or blower and retained at both sides of the knife-edge by laterally-movable guard-combs. The stiff bristles projecting through and above 35 the combs are then clipped off by horizontal knives or shears arranged above the combs.

In the accompanying drawings, which fully 40 illustrate our invention, Figures 1 and 2 represent vertical transverse sections of our improved machine for clipping or plucking seal-skins, shown respectively before and during the clipping action. Fig. 3 is a sectional front elevation; Fig. 4, a top view of the same; and Figs. 5 and 6 are detail top views, respectively, 45 of one of the retaining guard-combs and of the lower clipping-knife.

Similar letters of reference indicate corresponding parts.

A represents the supporting-frame of our 50 improved machine for clipping seal-skins, at the middle portion of which is arranged a

fixed knife-edged bar, B, that extends transversely from one side support of the frame to the other. Over this bar B the seal-skin to be clipped is tightly stretched by being wound upon a roller, C, at one side of the knife-edged bar and upon a second roller, C', at the other side of the same. The skin is connected to the rollers C C' by means of bands attached to the ends of the skin, which bands are of 55 such length that every part of the skin can pass over the knife-edge. By a suitable pawl-and-ratchet mechanism the rollers C and C' are intermittently operated, so as to move the skin forward over the knife-edge at the proper 60 time.

Above the knife-edged bar, and of equal width with the same, is arranged a bellows or other air-forcing apparatus, D, which is supported on frame A and provided with a nozzle, D', the narrow discharge-orifice of which is vertically above the knife-edged bar B. The bellows D is operated by means of a treadle, E, which is connected by cords or pivot-rods a to the upper movable portion of the bellows, and by weights f, which are hung to cords d, passing over pulleys b b at the top of frame A. The weights f open the bellows as soon as the 65 treadle is released by the foot.

The treadle E is also connected by a cord, e, 70 passing over a pulley, e', to the rear end of a slotted lever-arm, g, which turns loosely on the shaft of a ratchet-wheel, g', and pinion g'', which latter intermeshes with gear-wheels g''' at the ends of the shafts of the winding and 75 unwinding rollers C C'. The short shaft of the ratchet-wheel g' and pinion g'' is supported in suitable bearings of frame A. A spring-pawl, g⁴, is pivoted to the lever g and a check-pawl, g⁵, to the shaft of the roller C. The pawl g⁴ passes over the teeth of the ratchet-wheel on depressing the treadle E, but engages the same on the return motion of the lever by the action of a spiral spring, h, which is attached to the rear end of the lever g and frame A. 80 The return motion of the lever g, imparted by spring h, causes the pawl g⁴ to engage the ratchet-wheel g', so as to turn the same and pinion g'', which latter turns the gear-wheels g''' in opposite direction, so as to produce the 85 unwinding of the skin from the front roller, C, and the winding up of the same on the rear 90 95 100

roller, C'. The seal-skin stretched over the knife-edged bar is thereby moved forward for a short distance. Before the skin passes over the knife-edged bar B it passes over a transverse tension-rod, i, the ends of which are connected by springs i' to the side standards of frame A, as shown in Figs. 1 and 3. This tension-rod prevents the too tight stretching of the skin and facilitates the motion of the same over the knife-edge.

The treadle E is furthermore connected, preferably at both ends, by fixed and headed pins, l, to slotted pivot-links, l', which are applied to the lower ends of vertically-guided and spring-cushioned connecting-rods l''. These are applied at the upper ends to guide-plates m, which are guided by parallel slots on fixed pins of frame A, as shown in Figs. 1 and 2. The guide-plates m are centrally recessed at their upper ends for the bar B.

To the lower parts of the guide-plates m are pivoted the shanks n of horizontal guard-combs F, which are arranged above and symmetrically to the knife-edged bar B, and pressed outwardly by a V-shaped spring, n'. The inclined rear sides of the shanks n of the combs F move, during the downward motion of the treadle, along anti-friction rollers n² of fixed side plates, n³, of frame A, the joint action of the slotted guide-plates and rollers n² serving to close the combs over the portion of the skin which is at that moment above the knife-edge. The side plates, n³, and rollers n² may be set somewhat higher or lower by means of wedge-

keys n⁴, so as to secure the exact position of the combs close to the narrow strip of skin, above the knife-edge. Above the guard-combs F are placed two horizontal clipping-knives, G, the inner cutting-edges of which are arranged in the form of an obtuse-angled V, as shown in Fig. 4, and operated by a crank-handle, G', at one end, so as to exert a shear cut upon the bristles projecting above the combs. The joint motion of the knives G is obtained by action of the outer pins, p, of the crank G' upon the upper and lower knives on swinging the crank around the intermediate fulcrum, p', as indicated by arrows in Fig. 4. Both knives are provided with inclined slots p², by which they are enabled to slide along the fulcrum p'. The upper knife is furthermore provided with a slot for the outer pin, p, which passes through the same to the lower knife, as shown clearly in Figs. 4 and 5.

By depressing the treadle a strong current of air is thrown by the bellows upon the narrow strip of skin which is at the time above the knife-edge, the current forcing the soft hair of the fur down and parting it at both sides of the knife-edge, so as to return the soft hair or wool and protect it against injury in clipping or removing the bristles, which project through the teeth of the combs.

By a motion of the operating-crank of the knives the projecting bristles are clipped off

close to the skin, or they may be plucked by pinchers or removed by other devices in case no knives are desired to be used. The knives, however, are preferable, as they accomplish the clipping operation across the whole width of the skin at one operation, and at that portion which is above the knife-edged bar. On the release of the treadle the bellows opens, the combs are raised and moved away from each other, and the skin is fed forward for a short distance over the knife-edged bar, so as to expose an adjoining strip to the action of the current and to the clipping-knives, as described. The clipping operation is repeated until the entire skin is freed of the stiff water-hair or bristles, which is in this manner accomplished at a considerable saving of time and expense as compared with the clipping or plucking of the skin by hand.

Having thus described our invention, we claim as new and desire to secure by Letters Patent—

1. In a machine for clipping seal-skins, the combination of a knife-edged bar and means for stretching and intermittently feeding the skin over the bar with an air-forcing apparatus arranged above the knife-edged bar, substantially as specified.

2. In a machine for clipping seal-skins, the combination of a knife-edged bar and means for stretching and feeding the skin over the same with oscillating guard-combs arranged symmetrically at both sides of the bar, substantially as set forth.

3. In a machine for clipping seal-skins, the combination of the knife-edged bar and means for stretching and feeding the skin over the bar with an air-forcing apparatus above the bar and with oscillating guard-combs arranged at both sides of the bar, substantially as set forth.

4. In a machine for clipping seal-skins, the combination of a knife-edged bar and means for stretching and feeding the skin over the bar with an air-forcing apparatus above the bar, with oscillating guard-combs, and with clipping-knives above the same, substantially as specified.

5. The method herein described of plucking seal-skins, consisting in first stretching the skin tightly over a knife-edged support, then forcing the soft hair back by a strong air-current, next retaining and protecting the soft hair by suitable guard devices, and finally clipping or plucking the stiff projecting hair or bristles, all substantially as specified.

In testimony that we claim the foregoing as our invention we have signed our names, in presence of two witnesses, this 6th day of October, 1880.
